United States Patent Office.

ADDISON CROSBY, OF WESTFIELD, NEW YORK.

Letters Patent No. 91,611, dated June 22, 1869.

IMPROVED BURIAL-CASE.

The Schedule referred to in these Letters Patent and making part of the same.

To all whom it may concern:

Be it known that I, ADDISON CROSBY, of Westfield, in the county of Chautauqua, and State of New York, have invented a new and improved Burial-Case; and I do hereby declare that the following is a full, clear, and exact description thereof, which will enable those skilled in the art to make and use the same, reference being had to the accompanying drawings, forming a part of this specification.

This invention relates to a new and useful improvement in the construction of leaden burial-cases, and has for its object economy in the manufacture of the same, strength and lightness combined, facility in making the cases air-tight, and an improvement in the general appearance and finish of the same.

Leaden burial-cases or coffins have been used from a very remote period, but they have not been very generally adopted, on account of the expense attending their manufacture, their extreme weight, and unsightly appearance.

The present invention fully obviates these objections.

In the accompanying sheet of drawings—

Figure 1 is a plan or top view of my invention, partly in section.

Figure 2, a side view of the same, partly in section.

Figure 3, an enlarged transverse central section of the same, taken in the line $z z$, fig. 1.

Figures 4, 5, 6, 7, 8, 9, and 10, sectional views of different parts of the same, drawn on an enlarged scale, for the purpose of exhibiting the details of construction.

Similar letters of reference indicate corresponding parts.

The burial-case is constructed of a galvanized-iron frame, over which the sheet-metal (lead and tin, or lead and other metal combined and rolled in sheets,) is secured.

The iron frame is made as follows:

The rim A of the bottom is made of sheet-iron, doubled and bent in angle-form, as shown clearly in figs. 3 and 6; and this rim A is perforated at its upper edge, at suitable distances apart, to receive the lower ends of upright pieces B, which are also made of sheet-iron folded, swaged, or rolled in T-form.

Bottom pieces, C, are also fitted horizontally in the rim A, at suitable distances apart, the bottom pieces C being constructed precisely like B.

The construction of C, or the way in which they are folded or swaged, is shown clearly in fig. 9.

The ends of B C are slotted longitudinally, as shown at a, (see fig. 6,) so that one portion formed by the slot will pass into the perforations of rim A, and the other part lap over one side of A.

After these pieces are thus fitted in the rim, they are secured by solder or by rivets.

The tops of the upright pieces B are fitted into a rim, D, in the same way that they are fitted into A.

The rim D is folded or swaged in T-form, like the pieces B C, (see fig. 5,) the top or lid being fitted and secured on D.

The top or lid is composed of a rim, E, which is constructed of a strip of sheet-iron, having transverse arched bars, F, attached, which are folded or swaged in T-form, like the pieces B C.

This top or lid is braced by one or more longitudinal flat strips, G, transverse strips G X, and diagonal strips H, as shown in fig. 1, said strips being secured in position by solder or by rivets.

The lower part or body of the burial-case is stayed by longitudinal, oblique, or inclined rods, I, at each side, as shown clearly in fig. 2.

The several parts described, which compose the frame of the burial-case, are all designed to be galvanized.

The rim E of the top is crimped or folded to form a pendent lip, b, to fit into the fold of the top rim D of the body of the case, (see fig. 4,) E being secured to D by screws e.

The covering of the metallic frame is composed of lead and tin, or, instead of tin, some other metal, such as zinc, will answer, although tin will probably be most generally used.

These two metals are rolled together, to form sheets of the requisite thickness.

In applying this covering to the frame, the lead side or portion k is placed in contact with the frame.

The object of an exterior tin surface, l, or a surface of other material or metal than lead, is to obtain a polished outer surface.

Lead will not receive a polish, but tin or zinc, especially the former, may be beautifully polished, so as to add in an eminent degree to the appearance of the burial-case.

The bottom covering J is cut out to correspond to the bottom of the frame, and the side covering K is cut out of a proper width, corresponding to the height of the body of the frame, and the edges of the bottom J and side K are lapped and stitched together with fine wire, d, brass or copper wire being preferable. (See figs. 7 and 8.)

In addition to this connection, the joint or seam may be soldered at the outer and inner sides of the stitching, and also between the lapped edges beyond the stitching, and the stitching covered by a longitudinally-slotted or slotted tube, L, soldered in proper position. (See more particularly figs. 3 and 8.)

By this arrangement, a very secure air-tight joint or seam is obtained.

The upright joint or seam of the side covering, of which there may be one or more, is formed by stitching and soldering in the same way as the side covering and bottom are connected, but no tubular covering, L, is required.

The bottom J is secured to the cross-pieces C by metal straps f, and solder, rivets, or wire, (as shown in fig. 9,) and underneath the bottom J, wooden strips, plank, or board, M, may be secured by wires g, which pass up through the strips and around the cross-pieces C of the frame.

Wooden strips, N, are also inserted between the cross-pieces C, on the top of the bottom J, as shown clearly in fig. 9.

The frame of the top or lid of the burial-case is covered with the rolled sheet-lead and tin O, connected to the frame by solder or rivets, and the edge of O may extend beyond the edge of said frame, and the edges of O and K connected by solder after the lid is screwed on the body or main portion.

This is done, of course, after the body is deposited in the burial-case.

The case is provided with a lining, P, of any suitable or desired fabric, hemmed at its top and bottom, through which hems, rods h pass; the latter being fitted in eyes j, secured by solder to the inner side of the case. (See figs. 4 and 10.)

Having thus described my invention, What I claim as new, and desire to secure by Letters Patent, is—

1. A burial-case, composed of a frame constructed of sheet-iron strips, rolled, folded, or swaged in angle-form, and covered with sheet-lead, or sheet-lead and tin, or other metal, rolled out, in contact with each other, substantially as shown and described.

2. Securing the pieces B C of the frame to the rims A D by slitting the pieces B C longitudinally at their ends, and inserting one part of said pieces formed by the slits in perforations in A D, or in the fold of the same, and the other part lapping over one side of the same, substantially as herein shown and described.

3. The diagonal, inclined, or oblique stays or brace-rods I I, when applied to or combined with a frame, constructed of sheet-metal strips, folded, rolled, or swaged in angle-form, substantially as shown and described, and for the purpose specified.

4. Joining the edges of the parts of the burial-case, comprising the covering, by stitching the edges with fine wire, and then soldering the same; and either with or without the tubular cap L.

5. The securing of the lining P in the case by means of the rods h, fitted in the hems in the lining, and secured in the eyes j, substantially as shown and described.

The above specification of my invention signed by me, this 17th day of July, 1868.

ADDISON CROSBY.
